ASPIRATING PISTON AND PLUNGER COUPLING

Stanley J. Sarnoff, 3 Peaks Hill Road, Bethesda 14, Md.

Filed Mar. 12, 1962, Ser. No. 179,085

9 Claims. (Cl. 128—218)

This invention relates to a hypodermic cartridge holder and associated cartridge.

In a common form of hypodermic injection apparatus, there is provided a one-use cartridge of medicament. This cartridge usually includes a hollow needle at one end thereof and a piston at the other end, with fluid medicament therebetween. When the cartridge is inserted within a cartridge holder, a plunger forming part of the holder may be coupled with the piston and then forced in to move the piston toward the needle to expel the fluid content of the cartridge through the needle.

It is an object of this invention, in such a device, to provide for automatic coupling and decoupling of the piston and plunger.

It is a further object of the invention to provide in such an automatic coupling and decoupling device a structure to enable withdrawal or aspirating movement of the piston, after the needle has been inserted into the body of a patient, to ascertain whether the needle has been inserted into a vein or artery.

Other objects will be made clear upon consideration of the following specification when taken in conjunction with the accompanying drawings in which:

FIG. 1 is a plan view, partly in section, of one form of holder embodying a plunger and coupling arrangement of the invention;

FIG. 2 is a plan view of a cartridge embodying a piston coupling forming part of the invention;

FIG. 3 is a plan view and partly in section, of a modified form of holder and cartridge embodying the invention, showing the cartridge partially inserted in the holder and in coupled relationship to the plunger;

FIG. 4 is a view of the parts of FIG. 3, with the cartridge in operative position and the plunger coupled to the piston;

FIG. 5 is a plan view of the plunger, partly in section;

FIG. 6 is an end view of the coupling end of the plunger;

FIG. 7 is a plan view of a button forming part of the coupling means;

FIG. 8 is a plan view, partly in section, of the coupling end of a different form of plunger.

Referring to the drawings with greater particularity, in FIGS. 1 and 2 there are illustrated a holder 10 and a cartridge 12.

The holder comprises a barrel 14 which may be windowed as at 16 to expose a cartridge therewithin and provided at one end with an internally threaded opening 18 to threadedly receive the threads 20 on the needle end of the cartridge 12. The opposite end of the barrel is open and its outer wall is provided with two diametrically opposed pins 22 pivoting a hub 24 by means of two legs 26 integral with the hub, straddling the barrel and pivoted on the pins. The hub may further be provided with finger pieces 28 for convenience in manipulation of the holder. Reciprocable in a bore 29 centrally located in the hub is a plunger 30, the bore in the hub being of a size to snugly slidably accommodate the plunger, especially the right-hand end thereof, as seen in FIG. 1.

The cartridge 12 comprises a glass or plastic tube 32 containing a fluid medicament 33 and mounting a hollow needle 34 at one end with its passageway in communication with the medicament in the tube. The other end of the tube has within it a resilient piston 35 provided with a centrally located coupling button indicated generally as 36.

2

When the plunger is withdrawn through the hub to the right as shown in FIG. 1, and the hub is rotated on its pivotal mounting to swing it away from over the open end of the barrel, the cartridge 12 is inserted into the barrel, needle end first, and the cartridge and barrel are manipulated to threadedly engage the parts 18 and 20. Then the hub is swung back into alignment with the barrel and the plunger 30 is thrust in to automatically engage the inner end of the plunger with the button. This is possible because of the construction and central position of the plunger and button. The plunger comprises a metal or plastic rod having a thumb piece 40 at one end and a forked opposite end. While the furcations may be of any number, for convenience in further description of the invention, the plunger is described as bifurcated. The furcations extend for a considerable distance from said opposite end to provide, in the form of invention illustrated, two tines 42 which are normally biased by inherent resiliency to cause the free ends of the tines to spring apart. FIG. 5 shows the tines in the divergent relationship that they assume when the plunger, shown, for example, in FIG. 1, is thrust to its furthest left-hand position in that figure.

Referring to FIGS. 5 and 6, it will be seen that each of the tines at its end has an arcuate jaw 44, almost semicircular in extent, with a slight gap between the jaws. The jaws have an internal space 46 of a diameter to fit snugly about a conical head 49 forming part of the button 36 with the inturned ends of the fingers 48 snugly embracing the neck portion 50 of the button. The underside 52 of the head 49 is perpendicular to the longitudinal axis of the button and to the length of the piston. The inside faces of the fingers, indicated at 54 in FIG. 5 are parallel to the underface of the head 49 of the button when the plunger and button are coupled together. The button itself is of rigid material, as metal, hard rubber or plastic, coupled into the softer resilient material of the piston, with a face of a flange 56 on the button extending slightly above the adjacent face of the piston and with a neck 58 and a second head 60 embedded in the resilient material of the piston, the head 60 having a surface perpendicular to the length of the piston, said head, therefore, resisting pulling the button out of the piston, the flange 56 resisting thrust of the button into the piston.

Reverting to FIGS. 1 and 2, when the cartridge has been positioned in the barrel and the hub rotated to bring the plunger over the cartridge and in alignment with the button, the plunger is moved in a distance until the fingers 48 engage the conical head 49 of the button 36. At this time there is a portion of the plunger between the hub and the button relatively free of lateral restraint, enabling the tines, on further thrust on the plunger, to be sprung apart by the conical head, notwithstanding the holding together of the tines at a position further back along the plunger by the bore in the hub, and then snap under the head into locking engagement with the button. The bore 29, as has already been described, snugly slidably accommodates the plunger, and therefore the tines, when the plunger is retracted or drawn to the right, see FIG. 1, are forced into parallelism thus maintaining the coupling engagement of the plunger and piston. After initial movement of the plunger so as to effect coupling between the plunger and the piston, and after the needle has been inserted into a patient, the piston may be withdrawn by limited plunger retraction to determine whether the needle is in communication with a vein or an artery. Thus, within a substantial range of movement of the piston from its initial position at the right-hand end of the barrel, the piston may be reciprocated by the plunger, at will, without decoupling.

The piston may be thrust, by plunger action, toward

the needle, the finger end of the plunger thrusting against the flange 56 of the button. As the plunger is thrust forward, and when the piston is at or near the needle end of the cartridge, the bifurcated portion of the plunger leaves the hub and the tines are free to diverge under their inherent bias, thus disengaging the fingers from beneath the head of the button. The plunger is therefore now free to be retracted without withdrawal of the piston, to enable easy removal of the evacuated cartridge and placement within the holder of a filled cartridge.

In a modified form of plunger, a portion of which is shown in section in FIG. 8, the tines, whether there be two or more, need not have a bias imparted thereto to cause divergence of the fingers. Instead, the tines, while resilient, are normally biased to parallel position and the inner faces of the fingers have a slight bevel 64 imparted thereto so that upon retraction of the plunger after the dosage of medication has been delivered through needle 34, the fingers will be cammed apart to release the button, thus effecting uncoupling or disengagement of the plunger and piston. There is sufficient friction between the piston and tube to accomplish this result when the tines are not confined in the bore of the hub and they are free to spread apart.

Still greater ease in coupling of the cartridge with the plunger of either type described is effected with the modified form of holder described in connection with FIG. 3. The holder of FIG. 3 is of a type disclosed in Patent No. 2,956,563 to Stanley J. Sarnoff dated October 18, 1960, to which reference may be made for amplification of the disclosure herein. The holder, see FIGS. 3 and 4, comprises a barrel 70 having an end with a bore 72 therein and furcations, here shown as bifurcations, to form arms 74 which normally tend to spring apart. The arms have inturned lips 76 at their ends and cams 78 on their outer faces, and a ring 80 surrounding the arms is adapted to be slid from over the cams to the right, FIG. 3, to allow the arms to assume their sprung-apart position. The cartridge 12 may now be inserted into the holder by inserting the piston end first through the space between the lips 76. The plunger 39, which may be either type previously described, may preliminarily be advanced in the bore, which snugly slidably accommodates the plunger, to a position where it is easy for the tines 42 to be sprung apart and snap over the head 49 of the button 36, if the tines are not normally biased to open position. If the tines are normally biased to open position, the cartridge will move freely until the flange 56 of the button contacts the fingers 48. Further movement of the cartridge to loaded position in the holder will thrust the plunger back to normal initial operative position. In such operative position the bore 72 will provide a camming action and will hold the fingers on the ends of the tines of the plunger closed on the head of the button so that the piston may be retracted for aspirating purposes without piston detachment from the plunger. Upon movement of the coupling end of the plunger and piston close to the needle end of the cartridge, the coupling may be detached or become detached, as previously described.

In the case of the form of invention shown in FIG. 3 the plunger can be easily withdrawn without dragging the piston back with it, and the ring 80 may then be moved back, thus releasing the cartridge for removal from the holder. The holder may now be reloaded, as has already been described.

While particular embodiments of this invention have been illustrated and described, modifications thereof will occur to those skilled in the art. It is to be understood, therefore, that this invention is not to be limited to the particular arrangements disclosed, and it is intended in the appended claims to cover all modifications within the spirit and scope of this invention.

Having thus described the invention, what is claimed is:

1. A holder comprising a barrel adapted to receive a cartridge with a piston therein,

a hub, forming part of the holder, provided with a bore therethrough,
a plunger snugly slidably reciprocative in said bore, said plunger comprising furcated portions forming a

5 plunger portion slidable in the bore, said furcated portions comprising tines biased to diverge from one another and forced toward one another by movement of the furcated portion in to the bore, and
10 said furcated portion terminating in fingers directed toward each other adapted to engage the piston when the fingers are brought close together.

2. A holder comprising a barrel adapted to receive a cartridge with a piston therein,

15 said piston having a coupling button having a head with an underface of the head perpendicular to the length of the piston,

a hub, forming part of the holder, provided with a bore therethrough,

20 a plunger snugly slidably reciprocative in said bore, said plunger comprising a furcated portion forming a

plunger portion slidable in the bore, and

25 said furcated portion terminating in fingers directed toward each other adapted to engage beneath the head of the button on the piston, when the fingers are brought together, the face of the fingers adapted to directly engage the underface of the head being bevelled to permit easy disengagement of the plunger from the piston in a predetermined region of the plunger with respect to the barrel.

3. A holder comprising a barrel adapted to receive a cartridge with a piston therein,

30 said piston having a coupling button having a head with an underface of the head perpendicular to the length of the piston,

35 a hub, forming part of the holder, provided with a bore therethrough, and

40 a plunger snugly slidable in said bore, said plunger comprising an end portion adapted to be engaged by a thumb of an operator, an intermediate solid section, and an end portion, said end portion being furcated to form tines,

45 said tines being biased to diverge from one another and forced toward each other by movement of the furcated portion into the bore,

50 said tines having finger portions formed on the ends thereof, said finger portions being directed toward each other and adapted to engage the underface of the head of the button and there being a chamber formed between the fingers to accommodate said head.

4. A holder comprising a barrel adapted to receive a cartridge with a piston therein,

55 said piston having a coupling button having a head with an underface of the head perpendicular to the length of the piston,

60 a hub, forming part of the holder, provided with a bore therethrough,

65 a plunger snugly slidable in said bore, said plunger comprising an end portion adapted to be engaged by a thumb of an operator, an intermediate solid section, and an end portion, said end portion being furcated to form tines,

70 said tines being biased to diverge from one another and forced toward each other by movement of the furcated portion into the bore,

75 said tines having finger portions formed on the ends thereof, said finger portions being directed toward each other and adapted to engage the underface of the head of the button and there being a chamber formed between the fingers to accommodate said head,

the face of each finger, which is within the chamber, being bevelled.

5

5. A holder comprising a barrel adapted to accommodate a cartridge having a piston therein, said barrel having a hub at one end thereof and having furcated portions at the other end, said furcated portions forming arms integral with the hub, lips at the free ends of the arms which lips are directed toward each other, means for drawing the free ends of the arms toward each other to retain a cartridge within the barrel, 10 said hub having a bore therethrough, a plunger snugly slidably movable in said bore, said plunger including tines normally biased to diverge from each other and movable through said bore and inturned fingers on the free ends of the tines adapted 15 to be engaged with the piston when the tines are within the bore.

6. The combination with a barrel having a space receiving a cartridge therein, said barrel at one end thereof having a hub with a 20 bore therethrough, a plunger having resilient tines biased to diverge away from each other and slidably snugly in said bore whereby the tines when in the bore will be urged together and the bore will resist spreading action of 25 the tines, the free ends of said tines having fingers directed toward each other, said cartridge having a hollow needle at one end and a piston therein at the other end, 30 a coupling button affixed to the piston, said button having a head with a face opposed to the fingers whereby when the fingers are engaged with the said face, and the piston is near the hub of the holder, a body fluid may be aspirated into the cartridge via the hollow needle by a retraction of the 35 plunger, pulling the piston with it.

7. The combination with a barrel having a space receiving a cartridge therein, said barrel having at one end thereof a hub with a bore therethrough, a plunger having resilient tines biased to diverge away 40 from each other and slidably snugly in said bore whereby the tines when in the bore will be urged together and the bore will resist spreading action of the tines, the free ends of said tines having fingers directed toward each other, said cartridge having a hollow needle at one end and a piston therein at the other end, 45 a coupling button affixed to the piston, said button having a head with a face thereof perpendicular to the length of the piston and opposed to the fingers whereby when the fingers are engaged with the face and the piston is near the hub of the holder, a body fluid may be aspirated into the cartridge via the hollow 50

6

needle by a retraction of the piston, pulling the piston with it.

8. The combination with a barrel having a space receiving a cartridge therein, said barrel having at one end thereof a hub with a bore therethrough, a plunger having resilient tines biased to diverge away from each other and slidably snugly in said bore whereby the tines, when in the bore, will be urged together and the bore will resist spreading action of the tines, the free ends of said tines having fingers directed toward each other, said cartridge having a hollow needle at one end and a piston therein at the other end, a coupling button affixed to the piston, said button having a head with a face opposed to the fingers perpendicular to the length of the piston, and said fingers having bevelled surfaces to engage said face so that when the piston is near the needle end of the cartridge, the plunger can be cammed away from the head by retraction of the plunger.

9. A holder comprising a barrel adapted to accommodate a cartridge having a piston therein, said piston having a coupling button having a head with an undersurface on the head perpendicular to the length of the piston, said barrel having a hub at one end thereof and having furcated portions at the other end, said furcated portions forming arms integral with the hub, lips at the free ends of the arms which lips are directed toward each other, means for drawing the free ends of the arms toward each other to retain a cartridge within the barrel, said hub having a bore therethrough, a plunger having tines which tines are snugly slidable in said bore, and said tines having inturned fingers on the free ends thereof adapted to engage the undersurface of the head of the button and there being formed a space between the fingers to accommodate the head, the face of each finger, which is directed toward the space between the fingers, being bevelled.
